Primary Examiner — Karen E Kearney*Assistant Examiner* — Adam C Mager*(74) Attorney, Agent, or Firm* — ZANIP(57) **CLAIM**

The ornamental design for an underwater thruster, as shown and described.

DESCRIPTION

FIG. 1 is a first perspective view of an underwater thruster showing my design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines shown in the drawings depict portions of the underwater thruster in which the design is embodied that form no part of the claimed design.
